Patented Dec. 16, 1919.

FIG. 3.

FIG. 4.

INVENTOR:

Joseph T. Burgert,
Ex. Baker & Macklin.
ATTYS.

UNITED STATES PATENT OFFICE.

JOSEPH BURGERT, OF LAKEWOOD, OHIO, ASSIGNOR OF ONE-THIRD TO MAX P. GOODMAN AND ONE-THIRD TO GEORGE JANOWITZ, BOTH OF CLEVELAND, OHIO.

SPARK-PLUG.

1,324,875.

Specification of Letters Patent. Patented Dec. 16, 1919.

Application filed September 15, 1917. Serial No. 191,523.

To all whom it may concern:

Be it known that I, JOSEPH BURGERT, a citizen of the United States, residing at Lakewood, in the county of Cuyahoga and 5 State of Ohio, have invented a certain new and useful Improvement in Spark-Plugs, of which the following is a full, clear, and exact description, reference being had to the accompanying drawings.

10 This invention relates to spark plugs for use as the ignition terminal for internal combustion engines. The object is to provide, in a simple form, a plug which shall automatically drain liquid deposited within 15 the plug or on the electrodes and thus maintain the contact points clean and avoid the troublesome carbon deposit on the electrodes, which results with many plugs.

In accomplishing the above end, I provide 20 the central electrode of the plug in a form which presents a small cup for catching liquid gasoline or oil running down from the interior of the plug, the exterior of this cup coacting with the other electrode while 25 the interior is drained at one or more points comparatively distant from such other electrode. The side electrode carried by the wall of the plug is formed into hook shape, the inner extremity of which stands adjacent 30 to the outer edge of the cup of the central electrode. The sparking therefore, takes place from the high points of both the cup and the hook, and liquid on the hook or the outside of the cup, forming in a drop 35 at the lowest point, is immaterial.

By the above means I am able to preserve 40 the parts of the two electrodes where the spark is formed free from liquid and the resultant carbon deposit. My invention is hereinafter more fully explained and its essential characteristics are summarized in the claims.

In the drawing, Figure 1 is a side elevation of my improved spark plug; Fig. 2 is a 45 vertical central section of the same; Fig. 3 is a bottom plan of the plug; Fig. 4 is an enlarged cross section through the two electrodes, on the line 4-4 of Fig. 2 looking downwardly.

50 In the drawings, 10 indicates the outer or metal sleeve member of the plug. This is shown as having an externally threaded portion 11 adapted to screw into the engine head, an external annular shoulder 12 to

limit the movement, and an angular portion 55 13 for the application of a wrench. The side electrode 20 is carried by the lower end of the threaded sleeve 10. This electrode is made in the hooked form shown, its hooked portion lying in a radial plane and pointing 60 toward the head of the plug.

30 indicates the central electrode which is carried axially within a suitable insulating sleeve 40. This sleeve is shown as having an annular boss 41 which rests on an internal shoulder of the metal sleeve 10. A metal clamping bushing 50 is threaded into the upper portion of the sleeve 10 and bears downwardly against the upper shoulder of the boss 41. Suitable metallic rings may be 65 provided at the upper and lower shoulders of the boss 41 to make a gas-tight connection between the insulation and metallic sleeve.

The lower end of the rod 30 continues below the insulating sleeve in a stem 31, which 75 may be enlarged and abut the lower end of the insulation. This stem carries concentric with it a peculiar cup-shaped head 32. This head has a rounded end, and a conical wall surrounding the stem, and leaving an annular groove 33 within the cup and about the stem. One or more draining openings 34 are formed through the wall of the cup at 80 points relatively distant from the end 21 of the side electrode.

The conical form of the cup causes it to present a sharp upper edge which, at one point, stands adjacent to the end of the re-curved portion 21 of the side electrode. The sparking, therefore, takes place between these 90 points. As these points are the highest parts of the side hook and of the central cup, they are kept free from the liquid which may be deposited thereon. Any liquid deposited on the stem or the insulating support drains into the cup, and from thence 95 drains through the openings 34 away from the point 21.

The head 32 may be formed on the electrode rod 30 in any desired manner. It is 100 very convenient to make it an integral portion of the rod and to provide the enlargement 31 of the rod at 31 just above the cup. With such construction the rod 30 is inserted into the insulating sleeve from below. 105 The connection at the upper end of the central electrode rod may take any form desired. I have shown a nut 60 screwing onto

the rod and bearing against the upper end of the insulating sleeve 40. Above this nut is a clamping thumb nut 61.

It will be understood from the description that my spark plug is simple in construction and may be cheaply made. Due to the peculiar formation of the cup on the central electrode, I maintain the sparking parts constantly in clean condition for most 10 efficient sparking.

Having thus described my invention, what I claim is:

1. In a spark plug, the combination of a metallic sleeve, an electrode carried thereby and projecting wardly, an insulating plug within the sleeve, a rod occupying the sleeve carrying an electrode at its lower end, said last mentioned electrode having an upwardly facing cup-shaped head, the 20 edge of which is adjacent to the end of the electrode first mentioned, there being a groove within the cup-shaped wall below the insulating plug and a draining opening through the side wall of the cup, which 25 opening is relatively distant from the electrode first mentioned.

2. In a spark plug, the combination of a metallic sleeve, an electrode carried thereby, an insulating plug within the metallic sleeve,

a central rod within the insulating plug, an 30 extension on the rod below the insulating plug terminating in an integral upwardly facing cup, said cup leaving an annular groove between it and the body of the extension, draining openings through the wall 35 of the cup on opposite sides of the extension, the electrode first mentioned terminating adjacent to the wall of the cup at a point between the draining openings.

3. In a spark plug, the combination of a 40 metallic sleeve adapted to screw into the engine, an electrode carried thereby in the form of a hook with an upwardly extending inner portion, an insulating sleeve carried by the metallic sleeve, and an electrode rod 45 mounted in the insulating sleeve and having a head at its lower end, said head being approximately in the form of an inverted mushroom, the edge of which at one place stands adjacent to the point of the hook, said 50 head having a cavity behind its wall and there being a draining opening through the wall at a place relatively distant from the point of the other electrode.

In testimony whereof, I hereunto affix my 55 signature.

JOSEPH BURGERT.
